BACON AND EGG FRYER OR SIMILAR ARTICLE

Frank W. Reed and Gordon E. Miner, Paramount, Calif.

Application January 10, 1955, Serial No. 33,912

Term of patent 14 years

(Cl. D44—1)

Fig. 1 is a perspective view of a bacon and egg fryer or similar article, showing our new design.

Fig. 2 is a bottom plan view thereof.

Fig. 3 is a top plan view of the right-hand portion of the fryer as seen in Fig. 1 and with the cover removed.

Fig. 4 is an enlarged longitudinal sectional view, as taken on line 4—4 of Fig. 1.

Fig. 5 is an enlarged cross-sectional view, as taken on line 5—5 of Fig. 1.

We claim:

The ornamental design for a bacon and egg fryer or similar article, substantially as shown.
